FOUNTAIN BRUSH

Filed Sept. 4, 1943

Inventor:

H. L. Fischer

UNITED STATES PATENT OFFICE

2,416,684

FOUNTAIN BRUSH

Howard L. Fischer, St. Paul, Minn., assignor of
forty-nine per cent to George Ulwick, Minne-
apolis, Minn.

Application September 4, 1943, Serial No. 501,335

4 Claims. (Cl. 15—138)

1

This invention relates to fountain brushes and may be applied to a toothbrush where it is desirable to have the dentifrice stored in the hollow handle so that it can be dispensed quickly.

A feature resides in providing a valve means between the brush and the fountain handle which does not have any moving parts, but which valve is made by grooving the bearing shank on the brush-head and also grooving the opening leading into the handle which provides the bearing for the shank. These grooves are formed to overlap when they align so as to provide a passageway leading out of the handle and to the open channel extending longitudinally of the shank and leading to the bristles of the brush.

A feature of primary importance resides in providing a resilient valve means in the shank of the brush-head which will compensate for any wear or inequalities to keep the brush in the proper adjustment or in a set position and to maintain a close fit between the working surfaces.

It is also a feature to provide a locking means which holds the brush-head with its shank releasably locked to the handle. This locking means is accomplished by the resilient shank which is formed with a shoulder in the end thereof and a complementary shoulder is formed in the handle of the brush to engage with the shoulder on the shank of the brush-head.

This fountain brush is formed entirely of plastic and the body of the handle is formed with flexible side walls so that the dentifrice or liquid in the brush may be pumped out to the bristles of the brush when it is desired. The handle may be sold to the trade with a stopper in the same and the brush-head and shank may be applied to the handle by removing the stopper from the vial-like hollow handle providing the unit, including the brush-head with its supporting shank and the hollow handle. All of these parts are made of plastic material, such as Vinylite or any similar acetate material which is suitable for the purpose.

These features, together with other details, will be more fully and clearly hereinafter pointed out.

In the drawings, Figure 1 illustrates a side elevation of the brush, partly in section. Figure 2 is a side elevation of the vial-like handle showing the stopper for closing the same. Figure 3 illustrates the brush-head and shank removed from the handle. Figure 4 is an end view of the brush-head and shank taken on the line 4—4 of Figure 3.

The fountain brush A is illustrated in the form of a toothbrush to show the manner in which the invention may be applied thereto. It is apparent, however, that the invention may be applied to any fountain brush where a hollow handle 10 is desired for holding a supply of liquid or dentifrice and where a brush-head 11 is employed as associated with the handle 10.

2

The toothbrush A may be formed of two main parts, the hollow handle 10 which may be sold to the trade with a stopper 12, and the brush-head 11 which is adapted to be inserted into the opening 13 when the stopper 12 is removed. It is desirable that the handle 10 be transparent or sufficiently translucent so as to disclose at a glance the amount of liquid remaining in the handle 10.

10 The brush-head 11 includes the tufts of bristles 14 and the channel-shaped shank 15 formed with the longitudinally extending groove 16 along the inner surface of the same and leading into the tufts of bristles. The open groove 16 extends into the reduced shank portion 17 which fits into the opening 13 as illustrated in Figure 1.

The opening 13 which forms the bearing for the reduced shank portion 17 is formed with a complementary groove or passageway 18 which overlaps with the end of the groove or passageway 16. When the groove 16 overlaps with the passageway 18 and is in alignment therewith, the dentifrice may be pumped out of the handle 10 by squeezing the sides of the handle to force a quantity of dentifrice out into the groove 16 which will run down to the bristles 14 when the toothbrush is held upside down or with the bristles in a downward direction and the handle in an upward direction.

30 The upper edge 19 of the handle 10 is formed with a rounded surface and is adapted to fit into the annular groove 20 formed in the shoulder of the shank 15 which overlaps the upper edge 19 of the handle 10. This provides a close fitting joint between the shank 15 and the handle 10.

The reduced shank portion 17 is bifurcated as illustrated in Figures 1, 3 and 4 forming an open slot 21 between the sides forming the cylindrical-shaped reduced shank 17. When this portion of 40 the shank is molded of plastic material, the side portions flare outwardly so that the slot 21 is wider at the bottom than at the top. The lower end portions of the bifurcated shank 17 are formed with semi-annular ribs 22 which project slightly from the cylindrical surface of the shank portion 17. An annular shoulder 23 is formed in the handle 10 in which the ribs 22 are adapted to engage when the brush-head 11 is positioned in the handle 10 as illustrated in Figure 1. Thus, 50 when the brush-head is connected to the handle 10, the sides of the shank 17 are compressed slightly to provide a spring tension which is adapted to hold the brush-head 11 in any adjusted position in the handle 10.

This resilient shank end 17 provides a resilient connection between the brush-head 11 and the handle 10 so as to keep a close fit between these working parts and to permit the brush-head 11 to be rotated in the bearing 13.

60 When the groove 16 and the passageway 18 are

out of alignment, the shank 17 will act as a resilient stopper to close the handle 10 and prevent any liquid from being forced out of the handle.

The stopper 12 may be formed with a resilient shank 17 and with the projecting ribs 22 if it is desired. In this manner I provide a resilient shank end on the brush-head 11 which will take up any slight wear in the use of the brush as it is rotated in the bearing 13. The brush and handle are of a simple construction formed entirely of plastic material which may be injection or compression molded. The fountain brush may be applied to other forms of brushes than that illustrated and wherein the same principle is desired to provide a resilient close fitting joint between the brush-head and the fountain brush.

I provide a hole 24 through one of the lower corners on the base of the handle 10 which permits the brush A to be hung on a hook when it is desired. The advantages of the features set forth will be obvious and it is of primary importance to provide the resilient shank 17, together with the locking ribs 22 which engage the annular shoulder 23.

Figure 5 is an alternative detail of the shank of the brush-head and a portion of the handle in section. The shank of the brush 15 may be made with a straight tapered reduced portion 17 which is divided at 21 to provide a resilient shank 17.

The opening 13 into the handle 10 is tapered, being larger at the inner end 26 than at the outer end 27. Thus, when the bifurcated resilient shank 17 is inserted in the opening 13, it will fit the tapered opening 13 to releasably lock the brush shank 15 in the opening 13. Any pressure on the liquid within the handle 10 will cause the liquid to enter the slot 21 tending to expand the shank 17 and to hold the same locked in the opening 13 while pressure is exerted by the liquid in the handle 10.

Thus, I provide a frustro-conical opening 13 in the handle 10 and a similarly shaped resilient shank 17 which is adapted to fit into the opening 13.

I claim:

1. A toothbrush of the character described, including, a dentifrice containing body having an open neck portion, the internal wall defining the neck portion being formed with an inwardly facing groove having one of its ends opening into the body and its opposite end terminating spaced from the free end of said neck portion and a detachable bristle supporting head having a reduced bifurcated portion resiliently and rotatably mounted within the neck portion of the body, said bristle supporting head being formed with a longitudinally extending outwardly facing groove having one of its ends terminating intermediate the ends of one leg of the reduced bifurcated portion, whereby said last named end of the outwardly facing groove is moved into and out of alinement with the inwardly facing groove of the neck portion of the body during predetermined rotative movements of the bristle supporting head relative to said body.

2. A toothbrush of the character described including, a dentifrice containing body having an open neck portion, the internal wall defining the neck portion being flared toward the body and being formed with an inwardly facing groove, said groove having one of its ends opening into said body and having its opposite end terminating spaced from the free end of said neck portion, and a detachable bristle supporting head having

a reduced tapered bifurcated portion resiliently and rotatably mounted within the flared neck portion of the body, said bristle supporting head being formed with a longitudinally extending outwardly facing groove having one of its ends terminating adjacent the brush bristles and its opposite end terminating intermediate the ends of one leg of the reduced tapered bifurcated portion, whereby said last named end of the outwardly facing groove is moved into and out of alinement with said inwardly facing groove of the neck portion of the body during predetermined rotative movements of the bristle supporting head relative to said body.

3. A toothbrush of the character described including, a dentifrice containing body having an open neck portion, the internal wall defining the neck portion having its inner end terminating in an inwardly facing circumferential recess, said inner wall further being formed with a longitudinally extending groove having one of its ends opening through the recess and into the body and having its opposite end terminating spaced from the free end of said neck portion of the body, and a detachable bristle supporting member having a reduced bifurcated headed end adapted to seat with the circumferential recess and to be thereby rotatably connected within said neck portion of the body, said bristle supporting member being formed with an outwardly facing groove having one of its ends terminating adjacent the brush bristles and having its opposite end terminating intermediate the ends of one leg of the said bifurcated end, whereby said last named end of the outwardly facing groove is moved into and out of alinement with the inwardly facing groove of the neck portion of the body during predetermined rotative movements of the bristle supporting member relative to said body.

4. A toothbrush of the character described including, a dentifrice containing body having an open neck portion, the internal wall defining the neck portion having its inner end terminating in an inwardly facing shoulder, said internal wall of the neck further being formed with an inwardly facing groove having its lower end opening through said shoulder and into said body and having its opposite end terminating spaced from the free end of said neck portion, and a detachable bristle supporting member having a reduced bifurcated headed end for engagement beneath said shoulder to rotatably connect said member and body together, said member further being formed with an outwardly facing groove extending from the brush bristles to a point intermediate the ends of one leg of said bifurcated end, whereby said grooves are moved into and out of alinement with each other during relative rotative movements of the bristle supporting member and the body.
